ELECTRICAL CONTACT RESISTANCE HEATING AND SOLDERING DEVICE

Alexander Schoenwald, Auburn, N. Y.

Application January 24, 1941, Serial No. 375,780

2 Claims. (Cl. 219—26)

This invention relates to a new method and means for the development and utilization of heat by electricity, particularly applicable to use in connection with the heating of soldering tools, also parts to be soldered, stoves, and for the heating of various and sundry materials, objects and devices.

This invention utilizes the contact resistance phenomena, i. e., when two metals or electric conductors touch one another and electric current is passed through the joint formed thereby, said joint will show an electric resistance which is known as contact resistance.

It is a known fact that such electric contact resistance has a very low resistance value and, therefore, it has been very difficult and uneconomical to develop sufficient heat by such contact resistance for commercial purposes, because the necessary current intensities must be very high (approximately many times 10,000 amps.) and for this reason the conductors must be very heavy.

The principal object of the invention, therefore, is to provide a method and means of effectively applying the contact resistance principle for the development and utilization of heat for commercial purposes.

This invention makes it possible to develop sufficient heat quantities for commercial purposes by electrical contact resistance with such low current intensities that it is now practical with this invention to heat various objects, such as soldering tools, stoves under certain circumstances, and other devices, with greater efficiency than other forms of construction heretofore used.

This invention makes it possible to heat by electricity such devices as soldering tools, and the like, through the medium of direct metallic contact and without applying any intermediate insulating material between the heating elements or contacts and the object to be heated. Since intermediate insulating material is eliminated in the use of this invention, the heating elements or contacts may be made comparatively small, thereby greatly reducing the area of heat radiation and as a result thereof the loss of heat by radiation is considerably reduced. Since the heat is transmitted directly to the object to be heated through direct metallic contact without insulation, only a relatively small amount of heat energy is required.

The various electrical devices and appliances commonly used require certain materials or elements which my invention eliminates. For in-

stance, commonly known constructions employ insulating materials between the heating elements and the object to be heated. Obviously, the efficiency of such constructions is very low due to the fact that the amount of heat energy invested or used is much greater than the amount which is actually utilized in order to overcome the resistance of the insulating material. Another disadvantage of such commonly known constructions results from the fact that the heating elements used are usually built up either in the form of a wire or ribbon, either in the form of a spiral or coil, in association with insulating material with a space between each winding. This spacing enlarges the area of heat radiation, further decreasing efficiency. All such obstacles are overcome by the use of my invention employing the contact resistance principle.

A further object of my invention resides in providing a method and means which will overcome the many difficulties encountered with known electrical heating devices, which is simple and durable in construction, inexpensive to manufacture and very efficient in use.

With these and numerous other objects in view, my invention consists in the novel features of construction, combination and arrangement of parts, as will be hereinafter referred to and more particularly pointed out in the specification and claims.

In the accompanying drawing forming a part of this application,

Figure 1 is a schematic view illustrating the relationship of the essential elements to electrical connections;

Figure 2 is a top plan view showing the application of the invention to a soldering unit;

Figure 3 is a fragmentary longitudinal sectional view on an enlarged scale taken through the forward portion of the soldering unit;

Figure 4 is a transverse sectional view, as seen on the line 4—4 of Figure 3, looking in the direction of the arrows;

Figure 5 is a side elevational view of a modified form of soldering tool; and

Figure 6 is a schematic view of a modification of the invention, showing the use of polyphase currents.

Referring to the drawing, in which similar reference characters designate similar parts throughout the several views, and particularly to Figure 1 thereof, the numeral 1 designates a transformer having a primary winding 2 and a secondary winding 3, the primary winding having

conductor wires 4 for connection with a source (not shown) of electrical current. A switch 5 may be provided for controlling the flow of current through the primary winding or same may be disconnected from the source of current when necessary.

The upper portion of this Figure 1 illustrates a schematic arrangement of the contact resistance system consisting of three metal parts. The metal part 19 represents the element or device to be heated, made preferably of copper, which has a higher specific heat conductivity quality than the other two metal parts 17. These metal parts 17 represent contacts and are tapered toward their free or outer ends, as shown at 18, the extreme free ends thereof being in direct contact with the opposite sides of the metal part 19. The metal parts or contacts 17 are respectively connected with the ends of the secondary coil 3 as shown and transmit through contact resistance the current to part 19.

By this arrangement the highest resistance exists at the points of contact between the parts 17 and 19, at which points the main quantity of heat is developed. The parts 17 being in direct metallic contact with the metal part 19 and the metal of said latter part being of lower heat resistance than the parts 17, the developed heat at the points of contact between said parts 17 and 19 flows into the metal of part 19 where such heat can be accumulated as needed. The heat thus accumulated in the part 19 will not flow back into the metal parts 17, except in very small negligible amounts, because of the specific resistivity of the metals in the parts 17 and also by reason of the fact that the tapered portions 18 thereof build up an additional considerable resistance at the points of contact with the part 19 against such flowing back of heat. This arrangement operates substantially like a heat rectifier.

In this arrangement there is a combination of different kinds of resistances consisting of the resistance of the metal parts 17, the resistance of the metal part 19 and the resistance at the points of contact between the said parts 17 and 19. In order to obtain the highest efficiency in utilizing the heat which is developed at the points of contact between the parts aforesaid, the sum of the resistances of the metals in parts 17 and 19 should not be higher than several per cent, possibly not over 5%, of the sum of the resistance values at the two points of contact between said parts 17 and 19. Therefore, these metal parts 17 and 19 must be so dimensioned, shaped and formed that their total added resistance is as low as possible and still not dimensioned so small as to weaken their mechanical and electrical strength.

Experience has shown that the best results are obtained when the contact metal part 17 is so dimensioned that its length is not more than five times the length of the longest diagonal that can be measured on its cross-section.

As heretofore mentioned, my invention is particularly adapted for use in connection with an electric soldering tool, although same may be equally well adapted for use in other connections. For purposes of illustration, I have shown in Figures 2 to 4, inclusive, one adaptation of the invention embodied in a soldering unit.

This improved soldering unit includes in its construction the transformer 1 heretofore referred to. The secondary winding of the transformer is connected with bars 6 of high conductive material. These bars project forwardly from the transformer 1 and a block of heat resisting

insulating material 7 is disposed between the rear portions of the bars a short distance in advance of the transformer, said insulating block being formed with a threaded bore 8 to receive a pair 5 of screws 9 which are passed through openings 10 in the respective bars and engaged with threads in the bore of the block. These screws firmly mount the insulating block 7 between the bars and limit their movement toward each other. 10 A clamping bolt 11 passes through the opening 12 formed in one bar, with its head bearing against the outer side face of said bar, while the opposite threaded end of the bolt passes through a bushing 13 of insulation. This outer end of the bolt carries a winged nut 14 which, when turned home, exerts pull upon the bolt to flex the bars toward one another. Openings 15 are formed through the bars adjacent their free front ends to receive the stems 16 of contact parts 17 formed as heretofore set forth in connection with the illustration in Figure 1. The outer ends of the contacts 17 are tapered as heretofore described, for biting engagement with opposite side faces of the soldering tip 19, which is formed of metal, preferably copper, having a greater heat conductivity than the metal from which the contacts 17 are formed. When the nut 14 of the clamping bolt is tightened, obviously the tapered ends of the contacts 17 will be drawn into gripping engagement with the soldering tip 19 and firmly hold same therebetween. This tip 19 held in this manner may be readily removed and another tip substituted when it is found necessary or desirable. The soldering tip 19 will be quickly heated 20 when the current is applied and since said current may be cut off when use of the soldering tool is no longer required, said tip will cool quickly and corrosive oxidation to an appreciable extent will be eliminated.

40 The greatest efficiency is obtained when the volume of the metal part or tip 19 is not more than fifty times the sum of the volumes of the two contact metal parts 17. When polyphase current is used, in which instance there would 45 be more than two contacts 17 employed (as illustrated in Figure 6 of the drawing), then the volume of the metal part 19 should not be more than fifty times the sum of the volumes of all the contact metal parts 17 that may be used in that particular unit.

50 In Figure 5 there has been illustrated a further modified form of soldering tool wherein the conductor wire 20 of the cable or cord 21 passes through a handle 22 formed of insulating material and has its front end fixed to a U-shaped head 23 which is formed of conductive material and has spaced arms 24 carrying contacts 25 which correspond with the contacts 17 and extend inwardly from the arms for gripping a soldering tip 26 corresponding to the part 19. A clamping bolt 27 passes through the arms of the head or yoke 23 and has a winged nut 28 which bears against a washer or bushing 29 and, when tightened, serves to flex the arms toward each other holding the contacts 25 in gripping engagement with the soldering tip 26. A second cable 30 has its conductor wire 31 passing through the handle 32 of a clamp 33 and fixed to the clamp. This clamp is of a size to be conveniently handled and has jaws 34 and 35 and a screw 36 which is threaded through the jaw 34. When this form of soldering tool is in use a metal plate 37, which is adapted to have another metal plate 38 soldered to it, is clamped between the jaw 35 and the screw 36 and the screw tightened until

it has gripping engagement with the plate 37. The plate 38 is then disposed in overlapping engagement with the plate 37 and the soldering tip 26 applied to the plate 37 close to the edge of the plate 38. As soon as said soldering tip 26 touches the plate 37 a circuit will be completed, and this soldering tip will be quickly heated and solder melted to form a soldered joint between the plates.

In Figure 6 I have shown a further modified form of the invention in the form of a schematic view illustrating the use of polyphase currents. In this form, the numeral 39 designates a metal part having a specific high heat conductivity and it is the part to be heated. The metal parts 40 are the tapered contacts, similar to the contacts 17 in the form shown in Figure 1, same being tapered and having a lower heat conductivity than the part 39. These parts 40 are connected to current conductors 41 leading to a source of supply (not shown).

From the foregoing description of the construction of my improved invention, the operation thereof and the application of same to use will be readily understood, and it will be seen that I have provided a simple, comparatively inexpensive and efficient means for carrying out the objects of the invention.

While I have particularly pointed out the elements best adapted to perform the functions set forth, it is apparent that various changes in form, proportion and in the minor details of construction may be resorted to, within the scope of the appended claims, without departing from the

spirit or sacrificing any of the principles of the invention.

Having thus described the invention, what I claim is:

5. 1. In an electric heating device, a source of energy, a plurality of electrical conductors, a plurality of contact metals in circuit with said conductors and a metal part to be heated arranged in direct contact with said contact metals, said metal part being formed of a material of high heat conductivity with relation to the material of which said contact metals are formed, the length of each contact metal part being not greater than five times the length of the longest diameter measured cross-sectionally thereon, and ends of the contact metals being tapered to provide their greatest resistance at their points of engagement with the metal part to be heated.
10. 2. In an electric heating device operating on a contact resistance principle, a source of energy, a plurality of electrical conductors, three or more metal parts, one of said metal parts being formed of a material of higher heat conductivity than the other ones of said parts, the metal parts having the lower heat conductivity being connected with said electrical conductors and the other metal part of higher heat conductivity being gripped between and in direct contact with the free ends of each of the metal parts of lower heat conductivity, the latter being tapered smaller toward their respective free ends to enhance the contact resistance between the same and the metal part of higher heat conductivity.
15. 30.

ALEXANDER SCHOENWALD.
